REFRIGERATING APPARATUS

Application filed May 30, 1930. Serial No. 457,579.

The present invention relates to refrigerating apparatus and particularly to apparatus for returning lubricating fluid from the evaporator to the compressor of a refrigerating system of the compressor-condenser-expander type.

In a refrigerating system of the above type, the lubricant tends to accumulate within the evaporator and when, as in the embodiment illustrated, the liquid refrigerant is heavier than the lubricant the lubricant floats upon the top of the liquid refrigerant in the evaporator and acts as a deterrent upon evaporation. This accumulation of lubricant within the evaporator also tends to rob the compressor of necessary lubricating fluid. In order to maintain evaporating conditions substantially constant it is desirable to maintain the depth of the lubricant substantially constant and below a certain maximum.

Consequently one of the objects of this invention is to maintain substantially constant and below a certain maximum the depth of the lubricating oil which floats on top of the liquid refrigerant within the evaporator.

A more general object is to provide a means for maintaining substantially constant and below a certain maximum the depth of one liquid which floats upon the surface of a second liquid.

Further objects and advantages of the present invention will be apparent from the following description, reference being had to the accompanying drawing, wherein a preferred form of the present invention is clearly shown.

In the drawing:

Fig. 1 is a view showing in section a portion of an evaporator incorporating one embodiment of the invention;

Fig. 2 is a view showing diagrammatically the elements of a refrigerating system;

Fig. 3 is a fragmentary top view of a portion of the evaporator disclosed in Fig. 1; and

Fig. 4 is a fragmentary sectional view of an evaporator incorporating another embodiment of the invention.

The refrigerating system shown for illustrative purposes comprises a compressor 21 for compressing the refrigerant, preferably

sulphur dioxide, and for forwarding it to the condenser 22 where it is liquefied and collected in the receiver 23. The actuating means for the compressor preferably comprises a motor 24 connected by pulley and belt means 55 to the compressor 21. A supply conduit 26 conducts liquid refrigerant from the receiver 23 to an evaporator 27, while a conduit 28 conducts gaseous refrigerant from the evaporator 27 to the compressor 21, and pressure responsive means 29 is preferably connected in the return conduit 28 for controlling the motor 24 to provide alternating operating and idle periods of the compressor 21 according to the temperature of the evaporator 27.

Thus it will be seen from the above description that the compressor 21, the condenser 22, the receiver 23, and the conduits 26 and 28 constitute means for supplying the evaporator 27 with liquid refrigerant and also for removing gaseous refrigerant from the evaporator.

The preferred type of evaporator as disclosed in the drawing includes a tank 30 of a cylindrical form, having its one end closed by a valve plate 32, secured by bolts 33 in a supporting ring 34 surrounding the opening in the tank 30 of the evaporator. The valve plate has an outlet fitting 35 and an inlet fitting 36 supported thereon. The fittings form shut-off valves. The inlet fitting 36 for the liquid refrigerant enters into a passage through a boss 37 on the inner side of the valve plate. A supporting bracket 38 is attached to this boss and supports a float member comprising a closed non-sinkable float ball 39 and a float ball arm 40 which is pivoted to the bracket 38 and which operates through the medium of the rod 41, a needle valve (not shown) within the boss 37 for controlling the flow of liquid refrigerant into the evaporator.

In the embodiment shown in Fig. 1 a cup or skimmer 42 is mounted on the float member and preferably on arm 40 near the float ball 39. Within the cup or skimmer 42 is an inverted L-shaped lubricant tube 43 (Figs. 1 and 3) which extends upwardly for a short distance and then laterally towards the valve 100

plate 32 where it is supported by a larger outlet tube 44 which in turn is supported by the valve plate 32 and which communicates with the outlet fitting 35 by an aperture through the valve plate 32. The refrigerant gas is removed from the evaporator during operating periods of the compressor through the outlet tube 44 which has its outer end open for this purpose, and turned up to prevent liquid refrigerant from being removed through this tube. Adjacent the valve plate 32 there is a Venturi section 45 in the outlet tube 44 and the lateral end of the L-shaped lubricant tube 43 is positioned within the 15 Venturi section 45 of the outlet tube 44.

The position of the float member which comprises the closed non-sinkable float ball 39 and the float ball arm 40 is determined by the level of the liquid refrigerant within the 20 evaporator which is indicated by the reference character 46. When the level of the liquid refrigerant within the evaporator is lowered by evaporation the float member falls to a lower position and opens the needle valve which controls the flow of liquid refrigerant into the evaporator. When the level of the liquid refrigerant is raised by virtue of the needle valve being open, the float member 25 is raised and the needle valve is closed.

It is inevitable that a portion of the lubricating fluid of the compressor will be scrubbed up through the cylinders into the condensing chamber and thus be carried into the evaporator. The lubricant, being much 30 lighter than the liquid refrigerant, floats as a layer or upon the surface of the liquid refrigerant as indicated by reference character 47. It is desirable to keep the depth of this 35 layer of lubricant below a certain maximum and according to the embodiment shown in Fig. 1 when the depth of the layer of lubricant within the evaporator is more than is desired the excess lubricant overflows into the cup or skimmer 42. Since the cup is carried 40 by or attached to move simultaneously with the float member the position of which is determined by the level of the liquid refrigerant by reason of the fact that the liquid refrigerant is much heavier than the lubricant, a 45 substantially fixed distance is maintained between the level of the liquid refrigerant and the level of the lubricant, thus maintaining 50 the depth of the layer of lubricating fluid substantially constant.

Suction through the L-shaped tube 43 is provided by virtue of the position of the lateral end of this tube preferably within the 55 smallest part of the Venturi section 45 and through the Venturi action the lubricant is drawn up through the L-shaped connecting tube 43 and discharged into the stream of gaseous refrigerant when it is removed from the 60 evaporator through the outlet tube 44 and by 65 this arrangement the lubricant is carried back

to the compressor where it again serves its lubricating function.

In Fig. 4 a slightly different arrangement is used to carry out the principle of the invention. In this arrangement, instead of the cup 42 and the L-shaped connecting tube 43, a single tube 48 is used, this tube having one end serving as a skimmer and fastened to the float member by a bracket 49 and the other end preferably directed into the smallest part 70 of the Venturi section 50. The end of the tube which is fastened upon the float member projects vertically upward to the desired level of the lubricant indicated by the reference character 47.

A loop 51 is formed in the tube 48 for the purpose of increasing flexibility, necessitated by the fact that the one end of the tube is fastened to the movable float member. The tube 48 may be of the ordinary type which is somewhat flexible or of the so-called flexible type as is shown in Fig. 4.

The arrangement in Fig. 4 operates in a manner similar to the operation of the arrangement in Fig. 1. The float member determines the depth of the liquid refrigerant within the evaporator and the end of the tube 48 which is carried by the float member determines the level of the lubricant with respect to the level of the liquid refrigerant. The excess lubricant is skimmed into and carried through the tube 48 and discharged into the stream of the gaseous refrigerant and thus returned to the compressor.

While the form of embodiment of the invention as herein disclosed, constitutes a preferred form, it is to be understood that other forms might be adopted, all coming within the scope of the claims which follow.

What is claimed is as follows:

1. In a refrigerating system, an evaporator adapted to contain a gaseous refrigerant, a liquid refrigerant, and a layer of lubricating fluid, a float member for regulating the level of the liquid refrigerant, a duct for removing the gaseous refrigerant, and means communicating with said duct for removing lubricating fluid from said evaporator, said means including a portion separate from and attached to move simultaneously with said float member.

2. In a refrigerating system, an evaporator adapted to contain a gaseous refrigerant, a liquid refrigerant, and a layer of lubricating fluid, a float member for regulating the level of the liquid refrigerant, a duct for removing the gaseous refrigerant, and means communicating with said duct for maintaining the depth of said layer of lubricating fluid substantially constant, said means including a portion separate from and attached to move simultaneously with said float member.

3. In a refrigerating system, an evaporator adapted to contain a gaseous refrigerant, a

liquid refrigerant, and a layer of lubricating fluid, a float member for regulating the level of the liquid refrigerant, a duct in said evaporator for removing the gaseous refrigerant, and means discharging into said duct and having a portion separate from and attached to move simultaneously with said float member for maintaining the depth of said lubricating fluid substantially constant and for removing the excess of lubricating fluid from the evaporator.

4. In a refrigerating system, an evaporator adapted to contain a quantity of liquid refrigerant and a layer of lubricating fluid upon the surface of the liquid refrigerant, a non-sinkable float member within said evaporator, and means separate from and having a portion attached to said non-sinkable float member to move simultaneously therewith for maintaining the depth of said layer of lubricating fluid substantially constant.

5. In a refrigerating system, an evaporator adapted to contain a quantity of liquid refrigerant and a layer of lubricating fluid floating upon the surface of said liquid refrigerant, means for supplying said evaporator with said liquid refrigerant, a pivoted non-sinkable float member for regulating said means, and a second means separate from and having a portion attached to said pivoted non-sinkable float member to move simultaneously therewith for regulating the depth of said layer of lubricating fluid.

6. In a refrigerating system, an evaporator adapted to contain a quantity of liquid refrigerant and a layer of lubricating fluid floating upon the surface of said liquid refrigerant, a non-sinkable float member for regulating the level of said liquid refrigerant, and means separate from and having a portion attached to said non-sinkable float member to move simultaneously therewith for regulating the depth of said layer of lubricating fluid.

7. In a refrigerating system, an evaporator adapted to contain a quantity of liquid refrigerant and a layer of lubricating fluid floating upon the surface of said liquid refrigerant, a non-sinkable float member for regulating the level of said liquid refrigerant, and means separate from and having a portion attached to said non-sinkable float member to move simultaneously therewith for maintaining the depth of said layer of lubricating fluid substantially constant.

8. In a refrigerating system, an evaporator adapted to contain a quantity of liquid refrigerant and a layer of lubricating fluid floating upon the surface of said liquid refrigerant, a non-sinkable float member for regulating the level of said liquid refrigerant, and means separate from and having a portion attached to said non-sinkable float member to move simultaneously therewith for remov-

ing said lubricating fluid from said evaporator.

9. In a refrigerating system, an evaporator adapted to contain a quantity of liquid refrigerant and a layer of lubricating fluid floating upon the surface of said liquid refrigerant, a non-sinkable float member for regulating the level of said liquid refrigerant, and means separate from and having a portion attached to said non-sinkable float member to move simultaneously therewith for maintaining the depth of said layer of lubricating fluid substantially constant and for removing the excess lubricating fluid.

10. In a refrigerating system, an evaporator adapted to contain a gaseous refrigerant, a liquid refrigerant, and a layer of lubricating fluid, means for supplying the evaporator with the liquid refrigerant and for removing said gaseous refrigerant, a valve assembly for controlling the supply of liquid refrigerant, a float member pivoted to said valve assembly, and means having a portion separate from and attached to move simultaneously with said float member for regulating the depth of the layer of lubricating fluid.

11. In a refrigerating system, an evaporator adapted to contain a gaseous refrigerant, a liquid refrigerant, and a layer of lubricating fluid, means for supplying the evaporator with the liquid refrigerant and for removing said gaseous refrigerant, a valve assembly for controlling the supply of liquid refrigerant, a float member pivoted to said valve assembly, and means having a portion separate from and attached to move simultaneously with said non-sinkable float member for maintaining the depth of said layer of lubricating fluid substantially constant.

12. In a refrigerating system, an evaporator adapted to contain a gaseous refrigerant, a liquid refrigerant, and a layer of lubricating fluid, means for supplying the evaporator with the liquid refrigerant and for removing said gaseous refrigerant, a valve assembly for controlling the supply of liquid refrigerant, a float member pivoted to said valve assembly, and means having a portion separate from and attached to move simultaneously with said non-sinkable float member for removing said lubricating fluid from said evaporator.

13. In a refrigerating system, an evaporator adapted to contain a gaseous refrigerant, a liquid refrigerant, and a layer of lubricating fluid, means for supplying the evaporator with the liquid refrigerant and for removing said gaseous refrigerant, a valve assembly for controlling the supply of liquid refrigerant, a float member pivoted to said valve assembly, and means having a portion separate from and attached to move simultaneously with said non-sinkable float member for maintaining the depth of said layer of lubricating fluid substantially constant and for removing the excess lubricating fluid.

14. In a refrigerating system, an evaporator adapted to contain a gaseous refrigerant, a liquid refrigerant, and a layer of lubricating fluid, a non-sinkable float for regulating the level of the liquid refrigerant, and a skimmer 5 separate from and attached to move simultaneously with said non-sinkable float for maintaining the depth of said lubricating fluid substantially constant and for removing the 10 excess of lubricating fluid from the evaporator.
15. In a refrigerating system, an evaporator adapted to contain a gaseous refrigerant, a liquid refrigerant, and a layer of lubricating fluid, means for supplying the evaporator 15 with the liquid refrigerant and for removing said gaseous refrigerant, a valve assembly for controlling the supply of liquid refrigerant, a non-sinkable float member pivoted to said valve assembly, and means having a portion 20 separate from and attached to move simultaneously with said non-sinkable float member for receiving said fluid and for maintaining the depth of said layer of lubricating fluid substantially constant, said last named means also having another portion communicating with said first named means for 25 delivering the excess lubricating fluid collected in said second named means to said first named means in response to the removal 30 of gaseous refrigerant from the evaporator.
16. In a refrigerating system, an evaporator adapted to contain a gaseous refrigerant, a liquid refrigerant, and a layer of lubricating fluid, means for supplying the evaporator 35 with the liquid refrigerant and for removing said gaseous refrigerant, a valve assembly for controlling the supply of liquid refrigerant, a non-sinkable float member pivoted to said 40 valve assembly, and a flexible conduit having one of its ends attached to move simultaneously with said non-sinkable float member for receiving said fluid and for maintaining the depth of said layer of lubricating fluid substantially constant, said flexible conduit having 45 its other end communicating with said first named means for delivering the excess lubricating fluid collected in said conduit to said first named means in response to the removal 50 of gaseous refrigerant from the evaporator.

In testimony whereof I hereto affix my signature.

HARRY B. HULL.
